UNITED STATES PATENT OFFICE.

JOHN M. HANNON, OF HARTFORD, CONNECTICUT.

MACHINE FOR MAKING SAND MOLDS.

1,158,918.

Specification of Letters Patent.

Patented Nov. 2, 1915.

Application filed May 27, 1913. Serial No. 770,258.

To all whom it may concern:

Be it known that I, JOHN M. HANNON, a citizen of the United States of America, and resident of Hartford, in the county of Hartford and State of Connecticut, have invented 5 certain new and useful Improvements in Machines for Making Sand Molds, of which the following is a full, clear, and exact description.

This invention pertains to improvements 10 shown, described and claimed in Letters Patent of the United States granted to me Oct. 15, 1912, No. 1,041,274, in which the machine according to said patent comprises a 15 bed for supporting the separable parts of a flask and a yoke frame embracing and extending above the bed and adapted to be swung off to one side of the latter and having on opposite side members thereof sliding 20 able cope lifters with means for operating them, there was also provided at an upper portion of the yoke depending blade-like members between which the lifted cope would be brought to engagement so 25 when the yoke is swung sidewise carrying, and temporarily holding the cope therewith, the latter would not become displaced from the initial position which it occupied relatively to the yoke frame.

It has been found that the aforementioned 30 blade-like members required a nicety of adjustment and the external dimensions of different copes which might be used had to conform one to another in order to be permitted 35 to engage between the depending blade-like members and in such engagement to have a practically close fit therebetween.

The object of the present invention is to 40 provide means up to and against which the lifted cope may be brought and which in co-action with the cope lifters act for the retention of the cope against displacement relatively to the yoke, and which means is of greater simplicity than that formerly employed 45 for the corresponding purpose and requires no such nicety of adjustment as was formerly required and is adapted for the engagement with a suitable portion of the top of the cope instead of engagement with the 50 opposite vertical sides of the latter.

The invention is described in conjunction with the accompanying drawings and is set forth in the claims.

In the drawings:—Figure 1 is a side view 55 of the molding machine inclusive of the outer and inner yokes thereof upon upper

portions of which latter the improved appliances of this invention are shown. Fig. 2 is a similar side elevation showing the inner yoke and the lifted cope supported and 60 steadied thereby as swung to an offside position. Fig. 3 is a partial plan view and horizontal section as shown below the line 3—3, Fig. 1; and Fig. 4 is a front elevation of one side portion of the machine. 65

In the drawings, A represents the elevator bed and h and c the nowel and cope portions of the flask,—p representing the pattern plate the ends of which project beyond the ends of the flask and the cope has the end- 70 wise projecting lugs or extensions c².

C represents the inner yoke frame and D the outer yoke frame, these both being pivotally mounted at the lower portions of their side members. 75

The inner yoke frame is made at the top with offset brackets e e which intermediately thereof are firmly united to the upper ends of the opposite upright yoke members d d and project forwardly and rearwardly relatively to the latter, and the extremities of the brackets e are united by the horizontal parallel rigidly connected tie bars f f. 80

The opposite side members d d of the inner yoke are provided with slides E E which 85 are formed with guideways whereby they are engaged with and adapted for vertical movements relatively to the said side members; and these slides are equipped each with a cope lifter q and a pattern plate lifter r, 90 their normal locations and relations to the cope and pattern plate extensions being as represented in Fig. 4.

At the upper central part of the inner yoke C is a horizontal rockshaft t having 95 duplicated lever arms u rigidly affixed thereto near their outer ends, u² representing an operating lever arm for the rockshaft; and the lever arms u u are connected with the cope lifter slides E by links v. 100

On the tie bars f f comprised in the inner yoke are pairs of perforated bracket members w w held in any desired adjustment along the length of the tie bars by the set screws w². These brackets w have portions 105 extending below their places of attachment on the rods f with horizontal transverse holes w³ therethrough through which are engaged the shank portions of rods or bars K having offset or crank-like inner end portions or extensions s which are of such length as to extend inwardly beyond and

across the margin of the area corresponding to the cope, and up to which latter under the action of the cope lifters the top of the cope is brought to a steadyng engagement,—the same being held with a clamping bind between the cope lifters and the under sides of the offset extensions of the said members K. These members are both lengthwise adjustable, and the offset 5 extremities thereof are revolubly adjustable so that they may be positioned both properly over the cope of whatever size the same may be, and also nicely as to height so that the lifted cope will be brought to have 10 its top in firm contact engagement with such parts.

The engagement or bind between the cope lifters and the offset portions of the members K is such that when the inner yoke is 15 swung offside, as represented in Fig. 2, the cope will be steadily carried thereby and without any displacement or shifting relatively thereto and so that when the yoke is returned to its original upright position, 20 the cope will be in position to be let down again to match with the nowel with entire 25 precision.

I claim:—

1. In a machine for making sand molds, 30 in combination, an elevating bed for supporting the separable parts of a flask, and a yoke frame embracing and extending above the bed, pivotally mounted whereby it may be swung off to one side of the bed, provided 35 on the opposite side members thereof with cope lifters which are slidable on such side members, also provided with means for slidably operating such cope lifters, and provided at an upper portion thereof with 40 a member up against the under side of which the top of the cope, elevated by the cope lifters, may be brought to engagement.

2. In a machine for making sand molds, 45 in combination, an elevating bed for supporting the separable parts of a flask, and a yoke frame embracing and extending above the bed, pivotally mounted whereby it may be swung off to one side of the bed, provided

on the opposite side members thereof with 50 cope lifters which are slidable on such members, also having means for slidably operating such cope lifters, and provided at an upper portion thereof with a vertically adjustable member up against the under side of which the top of the cope, elevated by the 55 cope lifters, may be brought to engagement.

3. In a machine for making sand molds, 60 in combination, an elevating bed for supporting the separable parts of a flask, and a yoke frame embracing and extending above the bed, pivotally mounted whereby it may be swung off to one side of the bed, provided 65 on the opposite side members thereof with cope lifters which are slidable on such members, also having means for slidably operating such cope lifters, and provided at an upper portion thereof with a member which is both vertically adjustable and also transversely and horizontally adjustable, and up 70 against the lower part of which the cope, elevated by the cope lifters, may be brought to engagement.

4. In a machine for making sand molds, 75 in combination, an elevating bed for supporting the separable parts of a flask, and a yoke frame embracing and extending above the bed, pivotally mounted whereby it may be swung off to one side of the bed, provided 80 on the opposite side members thereof with cope lifters which are slidable on such side members, and having means for slidably operating such cope lifters, and provided at an upper portion thereof with oppositely located, rotatively adjustable, rods or bars 85 having offset extensions, revolubly carried by such bars, and against the under sides of which the cope, elevated by the cope lifters, may be brought to engagement.

Signed by me at Springfield, Mass., in 90 presence of two subscribing witnesses.

JOHN M. HANNON.
